[57] CLAIM

The ornamental design for a wall lamp, as shown and
described.

DESCRIPTION

FIG. 1 is a perspective view of a wall lamp showing my
new design;

FIG. 2 is a left side elevational view thereof, the right
side elevational view being a mirror image thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view of a lighting fixture show-
ing a second embodiment of my new design;

FIG. 8 is a left side elevational view thereof, the right
side elevational view being a mirror image thereof;

FIG. 9 is a front elevational view thereof;

FIG. 10 is a rear elevational view thereof;

FIG. 11 is a top plan view thereof; and,

FIG. 12 is a bottom plan view thereof.

The broken lines are shown for illustrative purposes
only.
